BROOM OR SIMILAR ARTICLE

Emanuel Gantz, Harrison, N. Y., assignor to Empire Brushes, Inc., Port Chester, N. Y., a corporation of New York

Application June 17, 1952, Serial No. 20,232

Term of patent 14 years

(Cl. D9—2)

To all whom it may concern:

Be it known that I, Emanuel Gantz, a citizen of the United States, residing at the city of Harrison, in the county of Westchester and State of New York, have invented a new, original, and ornamental Design for a Broom or Similar Article, of which the following is a specification, reference being had to the accompanying drawing, forming part thereof.

In the drawing:

Fig. 1 is a front elevational view of a broom or similar article, showing my new design;

Fig. 2 is a side elevational view thereof with the handle broken away for convenience of illustration; and

Fig. 3 is a cross-sectional view taken on line 3—3 of Fig. 1.

The back and other side not shown are substantially like the front and side shown.

I claim:

The ornamental design for a broom or similar article, as shown and described.

EMANUEL GANTZ.
